(57) **CLAIM**

I claim the ornamental design for a combined manually operated daily calendar, week counter, and quote displaying apparatus, as shown and described.

DESCRIPTION

FIG. 1 is a front elevational view of a combined manually operated daily calendar, week calendar, and quote displaying apparatus showing my new design;

FIG. 2 is a rear perspective view according to the first preferred embodiment thereof;

FIG. 3 is a front elevational view of a second embodiment, the only difference being the absence of the descriptions; FIG. 4 is a rear view according to the first preferred embodiment thereof;

FIG. 5 is a right side view according to the first preferred embodiment thereof;

FIG. 6 is a left side view according to the first preferred embodiment thereof;

FIG. 7 is a top view according to the first preferred embodiment thereof;

FIG. 8 is a bottom view according to the first preferred embodiment thereof;

FIG. 9 is a front elevational view of a third embodiment, the only difference being the horizontal orientation and the rounded edges;

FIG. 10 is a front perspective view of a fourth embodiment, the only difference being the rounded edges;

FIG. 11 is a rear perspective view according to the second preferred embodiment thereof;

FIG. 12 is a front elevational view of a fifth embodiment, the only differences being the absence of the descriptions and the rounded edges;

FIG. 13 is a rear view according to the second preferred embodiment thereof;

FIG. 14 is a right side view according to the second preferred embodiment thereof;

FIG. 15 is a left side view according to the second preferred embodiment thereof;

FIG. 16 is a top view according to the second preferred embodiment thereof;

FIG. 17 is a bottom view according to the second preferred embodiment thereof; and,

FIG. 18 is a front elevational view of a sixth embodiment, the only differences being the horizontal orientation and rounded edges.
